FEED-THROUGH SWITCH

Edwin H. Lockwood, Fairfield, Conn., assignor to
 Casco Products Corporation, Bridgeport, Conn.,
 a corporation of Connecticut

Application April 21, 1947, Serial No. 742,795

3 Claims. (Cl. 200—168)

1

This invention relates to electric switches, and more particularly to feed-through switches for connection in cords of heating pads and the like.

An object of the invention is to provide an improved switch of the type having a molded multi-part casing, wherein but few and extremely simple components are required, and wherein simple and quickly executed assembly operations are possible, to the end that considerable economy of manufacture is attained.

Another object of the invention is to provide a switch of the above type, wherein the switching member is arranged to have "off" positions on either side of an "on" position, in such a way that the condition of the switch may be readily determined by the sense of touch as well as visually.

A further object of the invention is to provide an improved feed-through switch having novel cord strain-relief means which are extremely effective and at the same time economical to produce and incorporate.

A still further object of the invention is to provide an electric switch which, in addition to the characteristics above outlined, has long life and is reliable in operation.

These and other objects are accomplished, in the embodiments of the invention illustrated, by the provision of a novel contact and connector assembly constituting a major part of the switch and yet involving relatively few and simple components the assembling of which may be quickly and economically carried out as by quick riveting operations, and by the provision of novel casing parts which cooperate with the said assembly to eliminate separate fastening means therebetween, and which to the fullest possible extent function also as parts of the switching mechanism itself, thereby either entirely eliminating or else greatly reducing the number of components or parts heretofore thought to be necessary. Moreover, with this arrangement the said casing parts may be made identical to each other, thus reducing considerably the initial tool cost, and keeping tool upkeep at a minimum.

The contact and connector assembly may be handled as a unit, and inserted as a unit between the casing parts, and this fact, together with the elimination of separate fastening means as such, result in lower part and labor costs.

The contact assembly preferably comprises a flat base plate, of insulating material, on which stationary contact members are secured and to which latter lead wires from electric cords are attached, the plate also having openings through

2

which a through lead wire from the cords may be passed back and forth, thereby to anchor the cords without employing separate anchorage devices.

- 5 Cooperable with the stationary contacts of the said assembly is a switch operator having pre-assembled to it a bridging contact member. The switch operator is held in its cooperable operative position by portions of the casing parts, 10 and by an edge portion of the base plate of the contact assembly unit, thereby eliminating the need for separate guide parts to control the path of movement of the operator, resulting in a further economy in the manufacture of the switch. 15 Moreover, the cooperation between the base plate and casing parts is such that shifting of the parts one on the other is effectively prevented, and therefore but a single draw bolt is needed to secure together the casing parts.
- 20 In one embodiment of the invention the switch operator is movable in either of opposite directions from the "on" position, to open the switch circuit, and by this arrangement a user may easily determine solely by the sense of touch 25 whether the switch is on or off.

Other features and advantages will hereinafter appear.

In the accompanying drawings:

- 30 Fig. 1 is a central axial section of a switch made in accordance with the invention.

Fig. 2 is a transverse section on line 2—2 of Fig. 1.

Fig. 3 is a plan view of the inside of a casing half.

- 35 Fig. 4 is a plan view of the base plate of the stationary contact assembly.

Fig. 5 is an elevation of a stationary contact member.

- 40 Fig. 6 is a side elevation of the assembled switch and

Fig. 7 is a view like Fig. 1 but showing a modification wherein the switch operator is movable from an "on" position in either of opposite directions to "off" positions.

- 45 Referring to Figs. 1, 2 and 6 the switch of the present invention comprises a casing 10 which preferably has a shape convenient for holding in the hand, the casing being formed of two halves 11 and 12 molded of insulating material.

50 In conjunction with the casing 10 a novel unitary assembly 13 is provided, according to the invention, the said assembly comprising a base plate 14 which is preferably of insulating material, and comprising a pair of stationary contact

members 15 and a pair of two-conductor electric cords 16.

Referring to Figs. 1 and 5 each contact member 15 has a flat base portion 17 with an aperture 18, the base portion having an extended end 19 the tip 20 of which is bent at right angles and is of generally cylindrical shape.

As shown in Fig. 4 the insulating base plate 14 is of generally elongate shape having a curved side edge 21 in which a pair of notches 22 is provided to accommodate the bent tips 20 of the contact members 15, the base portions 17 of the members being secured to the plate 14 by eyelets 23 which pass through the apertures 18 in the contact members and through corresponding apertures 24 in the base plate 14. Due to the shapes of the notches 22 and locations of the apertures 24 in the base plate, the contact members 15 are securely locked in their operative positions shown and prevented from turning about the eyelets 23.

Prior to securing the contact members 15 to the base plate 14 the bared ends of lead wires 25 from the cords 16 are interposed between the members and the base plate, whereupon the laying-over of the eyelets secures the lead wires under the base portions of the contact members to form electrical connection therewith.

The cords 16 also have lead wires 26 which are joined together so as to constitute in effect a single through lead wire, and in accordance with the present invention a novel and simplified means for joining and anchoring the lead wires 26 are provided. Referring to Figs. 1 and 4 the base plate 14 is provided with a pair of openings or notches 27 in the side edge 28 opposite the edge 21, the said notches being of a size to receive and closely confine the lead wires 26, and the said wires are passed through the notches 27 from one side of the plate to the other, and secured together, as by a metal clamping sleeve 26a. In so arranging the wires 26 they are provided with reverse bends 29 on opposite sides of the plate 14, Fig. 2, and therefore the wires are effectively anchored against longitudinal shifting with respect to the base plate.

For cooperation with the stationary contact members 15 a manually operable member 30 is provided, having a finger-engageable portion 30a and an arcuate slide portion 31, said member carrying a metal plunger 32 in a recess 33, the plunger being spring-urged outwardly by a spiral compression spring 34, Figs. 1 and 2.

In accordance with the invention the switch operator 30, the base plate 14 of the stationary contact assembly, and the casing halves 11 and 12 are so arranged that the latter may be identical to each other and yet when brought together with the said operator and assembly interposed, will provide a slide for the operator and will clamp and position the base plate 14 of the assembly and prevent movement thereof, all without requiring additional parts or extra assembly operations. Also, the casing halves are shaped to provide a slot through which the finger engageable portion 30a of the switch operator may project. By the above organization the number of parts required by the switch and labor needed in assembly are considerably reduced.

Accordingly, as shown in Fig. 3, each casing half is made in the form of an elongate shallow shell having an oblong concavo-convex wall 35, and having side flanges 36 and 37 extending along opposite side edges of the said wall.

At its ends each casing half has a semi-circular notch or recess 38 which in conjunction with

similar recesses in the other casing half form opening at the ends of the casing 10 to admit the electric cords 16.

In the center of the flange 36 each casing half has an elongate notch 39, the said notches constituting a slot 39a when the casing halves are secured together, through which slot the switch operator 30 extends.

For the purpose of positioning and securing the base plate 14 of the contact assembly in the casing 10, the halves 11 and 12 thereof have ribs 40 located to engage edge portions 41 of the base plate, and have lugs 42 provided with cut-outs or recesses 43 for receiving and nesting the corners 44 of the base plate.

The casing halves are secured together by a bolt 45 which passes through centrally located apertured bosses 46 of the halves, the said bosses being sufficiently long to project into an aperture 47 provided in the base plate 14.

Ribs 48 are also provided on the bosses 46 to function as shoulders for engaging opposite sides of the base plate 14 whereby the latter is securely clamped and rigidly held when the bolt 45 is tightened to bring together the casing halves 11 and 12.

It will be noted that the nesting of the corners 44 of the base plate 14 in the recesses 43 of the casing halves, and the engagement of the edges 41 of the plate with the ribs 40 of the halves effectively prevent shifting of one casing half with respect to the other even though but a single draw bolt is used in securing together the said halves.

For the purpose of guiding the slide portion 31 of the switch operator 30, a curved track 49 is provided in each casing half, the said tracks and the curved edge 21 of the base plate 14, together with curved walls 50 provided in the casing halves adjacent and co-extensive with the tracks 49, accurately guiding the switch operator 30 in an arcuate path of travel.

Referring to Fig. 1 the plunger 32 of the switch operator is shown as bridging the stationary contact members 15, thereby closing the circuits through the switch. When the switch operator 30 is shifted from the position of Fig. 1 toward the right to a position as shown by the dotted lines of Fig. 1, the plunger 32 will be separated from the left contact member 15, and the circuit through the switch will be opened.

By virtue of the plunger 32 having a rounded end as shown, it will cooperate with the cylindrical tip portions 20 of the contact members 15 to produce a desirable detent action by which the operator 30 will be yieldably held in either closed-circuit position or open-circuit position.

As seen in Fig. 1, the inner surfaces of the flanges 37 of the casing halves extend closely adjacent the notches or openings 27 in the base plate 14 and serve to prevent the lead wires 26 from shifting laterally out of said notches.

By the above construction the manufacture of the feed-through switch may be economically carried out, since as will be seen, but few and simple components are required, and since the assembly of the components may be very quickly and easily done. For example, the attaching of the contact members 15 and lead wires 25 to the plate 14 may be readily accomplished by use of an eyelet or rivet setting machine and the connecting together of the wires 26 done with a foot or kick press. The inserting of the wires 26 in the notches 27 may be easily done by hand after the connecting together of the wires, and the wires are thus anchored without the use of separate anchoring clips or the like.

After the assembly comprising the plate 14, contact members 15 and cords 16 is completed, it may be placed between the casing halves 11 and 12 together with the preassembled operator 30, whereupon the bolt 45 may be applied and the casing halves secured together. This assembling operation may be quickly done, and does not require separate fastening or guide means for the parts within the casing 10, thereby resulting in the economies above mentioned.

I have found that the anchorage of the lead wires 26 as described above is extremely effective in preventing pullout of the cords 16 from the casing 10 even when the cords are under substantial tensile stress. Due to the fact that the wires 26 are joined to the wires 25 along their entire lengths in the cords 16, any pulls to which the cords may be subjected will be opposed mainly by the anchorage for the lead wires 26, thereby relieving from stress the connections effected to the wires 25 by the eyelets 23 and contact members 15, which stress could act to weaken said connections or cause failure thereof.

A modification of the invention, wherein the manually operable member of the switch may be shifted in either of opposite directions from its "on" position, to enable the condition of the switch to be ascertained solely by the sense of touch, is shown in Fig. 7. In this figure, parts which are similar to the parts shown in the preceding figures have been given the same characters.

As shown, the notches 22 of the base plate 14 are located centrally in the curved side edge 21 of the plate, that is, half way between the ends of the plate, instead of slightly off center as shown in Fig. 4. Also, the notches 39 in the flanges 36 of the casing halves are made longer, so that the slot 51 in the casing 10, through which the finger engageable portion 30a of the operator 30 extends, is longer than the notch 39a shown in Fig. 1.

When the switch operator 30 is in its circuit-closing position wherein the plunger 32 bridges the stationary contact members 15, as shown in Fig. 7, the finger engageable portion 30a of the operator is centralized in the slot 51. From this centralized position it may be shifted either to the right or to the left, whereupon the plunger 32 will separate from one or the other of the contact members 15 so as to open the circuit of the switch.

A user in operating the switch may thus determine solely by the sense of touch whether the switch is on or off. For example, if the user pushes the portion 30a of the operator to either one of the extreme positions wherein it occupies an end of the notch, he will know that the switch is in open circuit position. From this position it is merely necessary to push the operator in the direction in which movement is possible until the plunger 32 rides over the tip portion 20 of the engaged stationary contact 15 and bridges the said contacts. The detent action of the plunger 32 and spring 33 readily enable a user to ascertain when this new position has been reached, and he will then know that the circuit through the switch is closed. In a similar manner if the switch is in closed-circuit position to begin with,

a user may by the sense of touch set the switch by first shifting the operator 30 in either one direction or the other to the limit of its movement, which is then open-circuit position, and proceed as above.

This action of the switch whereby its condition may be ascertained by touch is of considerable advantage in connection with heating pads, in cases where it is difficult or inconvenient for a user to observe the condition of the operator 30, either because of darkness or disability.

Variations and modifications may be made within the scope of this invention and portions of the improvements may be used without others.

15 I claim:

1. In a switch, a plate having contact members thereon and lead wires connected with said contact members; a casing comprising two parts secured together and located on opposite sides of said plate and having cooperating shoulders supporting and positioning said plate; said casing including an inwardly-facing channel formed on the interior thereof opposite an edge of said plate; a switch operator slidably engaged in said channel, the edge of said plate opposite said channel having a guard-forming configuration such that the switch operator is prevented from leaving the channel by the edge of said plate.

2. A switch as claimed in claim 1 in which said switch operator includes thereon an element biased towards the edge of said plate, whereby the switch operator is urged outwardly into said channel.

3. A switch as claimed in claim 2 in which said each contact member is L-shaped, has one leg thereof fastened to a face of said plate, and the other leg thereof overlying said edge in the path of said biased element, the latter being of conductive material and serving, in a certain position of the operator, as an electrical connection between a pair of said contact elements.
